UNITED STATES PATENT OFFICE.

WILLIAM A. DROWN, OF ABINGTON, PENNSYLVANIA.

DESIGN FOR AN UMBRELLA OR PARASOL COVER.

SPECIFICATION forming part of Design No. 12,570, dated November 15, 1881.

Application filed October 7, 1881. Term of patent 14 years.

To all whom it may concern:

Be it known that I, WILLIAM A. DROWN, a citizen of the United States, residing in Abington, Montgomery county, Pennsylvania, have invented a new and original Design for an Umbrella or Parasol Cover, of which the following is a specification.

My design for an umbrella or parasol cover is fully shown in the accompanying drawings, 10 Figure 1 being a view of the cover as applied to the umbrella or parasol, and Fig. 2 an enlarged view of part of the cover.

The design comprises the broad bands *a b* and the intervening narrow band *d*, these bands 15 being of a corded character, and arranged parallel with and a short distance from the lower end of each segment, as shown in Fig. 2, so that when the complete cover is applied to the frame of the umbrella or parasol, as in Fig. 1, 20 the bands of one segment will coincide with

those of the adjacent segments, and the effect will be that of a triple band extending completely around the umbrella or parasol parallel with and a short distance from the outer edge of the cover.

I claim—

The within-described design for a parasol or umbrella cover or cover-segment, said design comprising a series of corded bands parallel with and a short distance from the lower or 30 outer edge of said cover or segment, the series comprising the broad bands *a b* and narrow intervening band *d*, as shown and described.

In testimony whereof I have signed my name to this specification in the presence of two sub- 35 scribing witnesses.

WM. A. DROWN.
